US00D677718S

(12) **United States Design Patent**
Huck et al.

(10) **Patent No.:** **US D677,718 S**
(45) **Date of Patent:** **** Mar. 12, 2013**

(54) **DRIVE GEAR FOR IMAGING COMPONENTS**

(75) Inventors: **Donald D. Huck**, Sanford, NC (US);
James H. Jones, Fayetteville, NC (US);
Matthew J. Morton, Holly Springs, NC (US); **Anthony D. Causey**, Fuquay Varina, NC (US)

(73) Assignee: **Static Control Components, Inc.**, Sanford, NC (US)

(**) Term: **14 Years**

(21) Appl. No.: **29/428,824**

(22) Filed: **Aug. 3, 2012**

Related U.S. Application Data

(63) Continuation of application No. 13/283,684, filed on Oct. 28, 2011, which is a continuation of application No. 12/902,625, filed on Oct. 12, 2010, now Pat. No. 8,073,364, which is a continuation of application No. 11/825,262, filed on Jul. 5, 2007, now Pat. No. 7,813,676.

Primary Examiner — Garth Rademaker

(57) **CLAIM**

The ornamental design for a drive gear for imaging components, as shown and described.

DESCRIPTION

The sole FIGURE is a perspective view of a drive gear for imaging components.

The broken lines depict a portion of the drive gear for imaging components which forms no part of the claimed design.

1 Claim, 1 Drawing Sheet
